UNITED STATES PATENT OFFICE.

WILLIAM L. CHURCH, OF NEWTON, MASSACHUSETTS, ASSIGNOR TO AMBURSEN COMPANY, OF BOSTON, MASSACHUSETTS, A CORPORATION OF NEW JERSEY.

DAM.

1,097,916.

Specification of Letters Patent.

Patented May 26, 1914.

Application filed October 16, 1913. Serial No. 795,464.

To all whom it may concern:

Be it known that I, WILLIAM L. CHURCH, a citizen of the United States, and a resident of Newton, in the county of Middlesex and 5 State of Massachusetts, have invented a new and useful Improvement in Dams, of which the following is a specification.

My invention relates to hollow, reinforced, concrete dams of the type described in the 10 patent to Howard L. Coburn, No. 870,934, and its object is to improve the construction of such dams in the manner hereinafter more fully set forth.

One embodiment of my invention is shown 15 in the drawings accompanying and forming a part of this specification, in which—

Figure 1 is a perspective view of a portion of a dam embodying my invention, and Fig. 2 is a cross-section of two contiguous 20 deck beams.

In the particular drawings selected for more fully disclosing my invention, 1 represents a flooring, preferably of concrete or the like, provided with separated longitudinally- 25 running grooves 2, 3, receiving respectively the lower ends of the separately molded concrete beams 5, 6, the beams 5 forming the up-stream deck and the beams 6 the down-stream deck or apron. These beams prefer- 30 ably are reinforced with metallic rods or other suitable members 12, 13, respectively, embedded in the beams near their under sides to form tension members. The upper end of each beam 6 rests against the off-set 35 7 of its coöperating beam 5 and the upper end of each beam 5 rests against the upper end of its coöperating beam 6 as shown. Where necessary I provide means for tying the upper ends of each pair of beams, and in the 40 present case I show bent rods 10, preferably of metal, the ends of which lie in the grooves 8 and 9 of the beams 5 and 6, respectively. The grooves formed by rabbeting the longi- 45 tudinal corners of the upper surface of each beam are filled with cementitious material 11, which uniting with the molded beams and surrounding the tie members effectually bond the several beams into a strong unitary structure. The inner portions 4 4' of the 50 beam-receiving grooves may, as shown, be filled with cement or the like.

It will be obvious that my improved dam may be built without such forms as are required in constructing the dam described in 55 the patent above referred to, thereby facili-

tating the work and saving a certain amount of expense, more especially as in a dam of the Coburn type, the last set of forms are necessarily inclosed within the dam structure and thereby lost.

The construction above described is applicable chiefly to dams of the smaller sizes.

It will be understood that various modifications may be made in the dam hereinbefore particularly described without depart- 65 ing from the principle of my invention.

I claim:

1. A hollow dam having its decks formed of a plurality of pairs of separately molded concrete beams, one member of each pair 70 supporting the other.

2. A hollow dam having its decks formed of a plurality of pairs of separately molded concrete beams, one member of each pair supporting the other, and means for tying 75 the upper ends of each pair together.

3. A hollow dam having its decks formed of a plurality of pairs of separately molded concrete beams, one member of each pair supporting the other, the longitudinal corners of the upper surface of each beam being rabbeted, and cementitious matter in the 80 grooves so formed between adjoining beams.

4. A hollow dam having its decks formed of a plurality of pairs of separately molded 85 concrete beams, one member of each pair supporting the other, the longitudinal corners of the upper surface of each beam being rabbeted, a metallic rod disposed in the grooves so formed between adjoining beams 90 on the up-stream side and adjoining beams on the down-stream side respectively.

5. A hollow dam having its decks formed of a plurality of pairs of separately molded concrete beams, one member of each pair 95 supporting the other, the longitudinal corners of the upper surface of each beam being rabbeted, a metallic rod disposed in the grooves so formed between adjoining beams on the up-stream side and adjoining beams 100 on the down-stream side respectively, and cementitious matter in each of said grooves for bonding the members of contiguous pairs and inclosing said rod.

6. A hollow dam comprising a flooring 105 provided with two longitudinal grooves, a plurality of separately molded concrete beams arranged in pairs, the lower ends of each pair of beams resting in said grooves, respectively, and the upper ends of each of 110

said pair being supported the one by the other, one member of each pair of beams being provided with an off-set for receiving its coöperating member, and means for tying together the upper ends of each pair of beams.

In testimony whereof, I have hereunto

subscribed my name this 15th day of Oct. 1913.

WILLIAM L. CHURCH.
